UNITED STATES PATENT OFFICE.

JOHN ERICKSON, OF CHICAGO, AND HERBERT F. OBERGFELL, OF RIVER FOREST, ILLINOIS, ASSIGNEES, BY MESNE ASSIGNMENTS, TO AUTOMATIC ELECTRIC INC., OF CHICAGO, ILLINOIS, A CORPORATION OF DELAWARE.

SUBSTATION TELEPHONE INSTRUMENT.

Original application filed April 5, 1922, Serial No. 549,733. Divided and this application filed February 8, 1926. Serial No. 86,911.

The present invention relates in general to a switch hook support for substation telephone instruments, but more particularly to an improved type of switch hook support having as the principal object the provision of a unitary structure that is simple and compact and which will be efficient in operation.

This invention is a division of our parent case Patent No. 1,590,355 issued June 29, 1926.

The features of the invention will become apparent upon a further perusal of the specification and will be explained fully herein-after, reference being had to the accompanying drawings comprising Figs. 1 to 4 inclusive. These drawings show various views of the automatic wall substation telephone set, embodying the improved type of switch hook support. Fig. 1 being a side view of the wall telephone showing the switch hook in its relative position on the telephone and also the calling and talking instrumentalities; Fig. 2 being a front view of the telephone looking from the left hand side of Fig. 1; Fig. 3, a front view of the switch hook support as a unit separated from the telephone; while Fig. 4 shows the inside of the cover of the telephone showing how the switch hook support is fastened to the cover and also its relative position therein.

The switch hook 6, and the springs 70 to 73, inclusive, which are controlled by it, are shown in Fig. 4 in the position they assume when the receiver is off the hook, the switch hook 6 being held up by the tension of the heavy spring 70 through the medium of the insulating bushing 69. The switch hook support 67 comprises an iron frame having a downwardly extending portion for mounting the springs 70 to 73, inclusive, and a number of turned up extensions which serve to mount the support onto the cover 3 of the telephone by means of the screws 10 and 11. The switch hook is pivoted in the support by the screw 68 as is most clearly seen in Fig. 3. In this figure, it will be noted that this extension of the switch hook support 67 into which the screw 68 is screwed is seemingly longer than necessary. This extension is purposely made long so as to enable the screw 68 to be turned out far enough to permit the removal of the switch hook 6

before all the threads of the screws are disengaged from the extension. In this manner the screw does not have to be entirely removed from the support 67 to dismount the switch hook 6 and there is not danger of losing it.

The switch hook 6 extends through an opening in the telephone cover 3 and also through a hole in the support 67 so that when the screw 68 is threaded through the long extension of the support, the extended portion of the screw which is not threaded will act as the pivot for the switch hook, while two upturned extensions of the support serve as bearings for the screw 68. The movement of the switch hook is limited by the T-shaped end of the hook striking against the flat side of the bracket 67.

The set of springs 70 to 73, inclusive, are fastened to the support 67 by means of a couple of screws, the springs being suitably insulated from each other and the support.

The features of the invention, having been described and ascertained in the foregoing, will now be pointed out in the appended claims.

What is claimed is:

1. In a subscriber's telephone set, a switch-hook mounting bracket, said bracket comprising a perforated frame portion and three parallel members extending at right angles thereto, two of said members being located on opposite sides of the opening in said frame and being relatively close together, a hook extending through said opening and between the members on opposite sides thereof, and a pivot screw having an extension passing through holes in said hook and the said members adjacent thereto and having a relatively long threaded shank engaging a threaded hole in the other member.

2. In a subscriber's telephone set, a switch hook mounting bracket comprising a plurality of extension members, an opening in said bracket, three of said members arranged parallel to each other and extending at right angles to said bracket, two of the members being located on opposite sides of said opening, a switch hook extending through said opening and between the members on opposite side thereof, a pivot screw having an extension passing through holes in said switch hook and said members adjacent thereto and

having a threaded shank engaging a hole in said other member, a spring combination mounted on the end of a long one of said extension members and arranged parallel thereto, one of the springs bearing on the end of said switch hook to move it when the receiver is off, and two other of said extension members extending at right angles to said bracket and bent parallel thereto at the ends for mounting the whole of said bracket on the wall of said telephone set.

3. In combination with a subscriber's telephone set, a switch hook mounting bracket comprising a plurality of extension members and an opening therein, a switch hook having a T-shaped end extending through said opening, three of said members arranged at right angles to said bracket and parallel to each other, a pivot screw extending through holes in said members and said switch hook and threaded in only one of said members, the movement of said switch hook around said pivot screw, being limited by said bracket.

25. 4. In combination with a subscriber's telephone set, a switch hook mounting bracket comprising a plurality of extension members and an opening therein, a switch hook having a T-shaped end extending through said opening, three of said members arranged at right angles to said bracket and parallel to each other, a pivot screw extending through holes in said members and said switch hook and threaded in only one of said members,

the movement of said switch hook around 33 said pivot screw, being limited by said bracket, and two other of said members arranged on opposite sides of said switch hook and bent at right angles and at the ends parallel to said bracket, for mounting said 40 bracket and switch hook on the wall of said telephone set.

5. In combination with a subscriber's telephone set, a switch hook mounting bracket comprising a plurality of extension members 45 and an opening therein, a switch hook having a T-shaped end extending through said opening, three of said members arranged at right angles to said bracket and parallel to each other, a pivot screw extending through holes in said members and said switch hook and threaded in only one of said members, the movement of said switch hook around 50 said pivot screw, being limited by said bracket, and a spring combination mounted on another of said members, one of said 55 springs being in operative relation to the T-shaped end of said switch hook to move it when the receiver is removed.

In witness whereof, I hereunto subscribe 60 my name this 27th day of January, A. D. 1926.

JOHN ERICKSON.

In witness whereof, I hereunto subscribe 65 my name this 27th day of January, A. D. 1926.

HERBERT F. OBERGFELL.
